DIRECTIONAL HOMO MIXER

Leslie C. Fisher, Farmingdale, N. Y., assignor to
Edwin G. Eppenbach, Manhasset, N. Y.

Application March 7, 1944, Serial No. 525,413

6 Claims. (Cl. 103—103)

This invention relates to what may be termed a directional homo mixer, a device for producing quickly a high degree of turbulence in any desired direction, such as horizontally or at various angles, of matter to be mixed or homogenized, and to the method of accomplishing the aforesaid results.

Heretofore agitating devices employed paddles, blades, turbines, and numerous similar mechanical means for producing movement of liquid media in order to mix and homogenize them. Their operation usually is based on the principle of simultaneously moving relatively large bodies of liquid, which entails the expenditure of a considerable amount of time and energy before the whole body of such liquid to be treated reaches the desired ultimate state of perfection.

It is the prime object of the present invention to provide new means for and a new method of quickly and thoroughly mixing a large, substantially still body of liquid at a minimum expenditure of energy, by means of a comparatively small but rapidly propagated stream of the same liquid within the large body of the still liquid, or by a plurality of such streams. In other words, instead of attempting to slowly move large portions of the liquid body by relatively large mechanical contrivances, it is proposed to create a fast propagated column of liquid, formed by an endless succession of relatively small portions of the liquid, so that a powerful stream is produced within the still liquid, and which stream is designed to rapidly displace or push relatively large volumes of the still liquid in the path of the stream, and to impart additional movement to the still liquid body portions, immediately surrounding that fast-moving stream.

It may be readily visualized from the foregoing that in utilizing such fast-moving column of liquid within a still body of liquid, a forceful movement and violent mixing of the liquid body will be achieved in a lesser time and to a more thorough degree than is possible by the heretofore employed, above-indicated devices.

Other objects of this invention are the provision of means for the production of a relatively small, concise or restricted column of fast-moving liquid within and directed against a relatively large, still body of liquid, and the method of moving a relatively large body of still liquid by way of such a concise or restricted fast-moving column of liquid created within that large, still body of liquid.

Another object of this invention is the provision of a device designed to produce within a

relatively still, large body of liquid a fast-moving one-directional column or columns of liquid medium, said column or columns having a substantially uniform cross-section, or having a gradually converging shape and utilizing such column or columns for the propulsion or steering of means equipped with said device.

The foregoing and still further objects and important advantages of the present invention will become more fully understood from the ensuing description in connection with the accompanying drawings, the latter illustrating for explanatory purposes only but a few embodiments of the present invention, and in which:

Fig. 1 indicates a vessel equipped with one of many possible forms of my liquid-column-producing device;

Fig. 2 is a plan view of the rotor of the device;

Fig. 3 is a sectional view taken on line 3—3 of Fig. 2;

Fig. 4 is a plan view of the cup-shaped outer stator member of the device;

Fig. 5 is a cross section taken on line 5—5 of Fig. 4;

Figs. 6 and 7 are fragmental detail views of different constructions of the outer stator member and of the rotor;

Fig. 8 is a plan view of the interior stator member; and

Fig. 9 is a cross section taken on line 9—9 of Fig. 8.

Referring specifically to the figures, in Fig. 1 there is shown a base 10, upon which is placed a vessel 11, provided with a suitable aperture 12 for the reception of the interior mechanism of my device. Covering aperture 12 and associated therewith in a liquid-tight manner is a collar or sleeve 13, which is provided with an outer flange 14, to which is secured a bearing housing 15.

This housing is preferably supported by a bracket 16 resting on base 10 and is secured to the flange of sleeve 13 connecting housing 15 with motive source 18, the latter being supported by base 10.

Motor shaft 19 passes through sleeve 13 and into housing 15 where it is coupled at 20 with rotor drive shaft 21, which is lodged in thrust bearings 22, secured at the interior end of a tubular center 23 of housing 15. The exterior portion of center 23 is equipped with a shaft bearing 24, in which shaft 21 operates. This shaft is provided

with a collar 25 held in place by screw cap 26 engaging the outer end of tubular center 23. Secured in the closed end 27 of housing 15 are sup-

porting or guide rods 28 for the stator of the device. Four of such guide rods are indicated,

but obviously a lesser or a greater number may be employed. Housing 15 is preferably provided with removable side covers 15' rendering the shaft bearing and other parts of the mechanism readily accessible.

The stator is composed of two telescoping members. The outer member 29 comprises a cup formation 30 provided with a central opening 31 and a peripheral ledge or flange 32 with a gradually inwardly curved outer surface. The interior shape of the ledge may be altered as indicated in Figs. 6 and 7, and as will be presently explained. Extending from the cup formation 30 there are supporting or suspension legs or arms 33, corresponding in number to that of stator guides or rods 28. Stator member 29 may be considered a housing for the other or inner stator member 34, which comprises a central body 35, from which again project legs or arms 36. Extending from and through central body 20 35 is a plurality of vanes 37 disposed at a tangent to a theoretical inner circle. Their outer edges are preferably curved to correspond with the interior curvature of cup or housing 30 of the stator member 29, and in cooperation with the latter these vanes provide a plurality of elongated, parallel and axially directed discharge passages from the stator. It will be observed that the interior ends of vanes 37 are inclined as at 38, the purpose of which shape will become 30 presently evident. Arms 33 and 36 of the stator members are provided with apertures 39 for the reception of threaded reduced end portions of frame or guide rods 28 supporting the stator assembly.

In Figs. 2 and 3 there is illustrated the rotor 40 of my device, which consists of an enlargement or head 41 forming a hollow structure composed of an outer, angularly shaped ledge 42, and a disc-like inner flange 43, between which outer and inner rotor parts are disposed inclined vanes 44. The center opening 45 of the ledge 42 registers with opening 31 of the outer stator member. Extending from flange 43 is a hollow reduced portion or sleeve 46 provided with an internal thread 47 for the reception of and the engagement with threaded end 48 of reduced drive shaft part 49. I prefer to pass threaded portion 48 through sleeve 46 of the rotor, and to attach lock nut 50 to the protruding threaded shaft end, and to secure that lock nut against movement by means of a pin or similar means 51.

Referring now to Figs. 6 and 7, these illustrations denote variations of the outer stator member and of the rotor, and especially of their end structures. In Fig. 6 the internally flanged end 32' of the stator member is provided with an annular interior recess 52, and ledge 42' of the rotor member is provided with a corresponding annular tongue or extension 53 adapted to operate within groove 52. In Fig. 7 flange portion 32'' of the outer stator member is provided with a male step 54, and in the ledge 42'' of the rotor there is arranged a female step 55 for the reception of male step 54. The groove and tongue provision of Fig. 6, and the step arrangement of Fig. 7, are intended to provide a more secure seal between the stator and rotor. It is obvious that any other suitable end construction providing a proper co-operation between the two members may be substituted.

Rotor 40 driven by shaft 21, which is actuated by motive source 18, operates between the two stator members. It will be observed that the

number of vanes of the rotor is less than the number of stator vanes and the resulting discharge ports of the stator. It will be also observed that the intake port of the device composed of stator opening 31 in registry with rotor opening 45 is disposed centrally. It will be noted that the discharge or ejecting passages formed between the wall of the outer stator member and the vanes of the inner stator member are parallel with one another and are disposed in axial direction in respect to the drive shaft 21. These passages may, however, be of a conical or converging construction, not shown. In order to properly journal the rotor within the stator I preferably provide one or two bearing sleeves 56 within the cylindrical center 57 of the interior stator member. The inclined ends 38 of rotor vanes 37 register with inclined edges 44' of the rotor.

Operation

The entire stator and rotor assembly forming a type of a turbine is intended to be submerged within a relatively large body of a substantially still liquid medium. As the rotor becomes actuated a continuous succession of relatively small portions of the still liquid is drawn axially through the intake port of the device and are forcefully discharged in axial direction in the form of a substantially cylindrical, converging cone shaped, or otherwise concise or concentrated solid stream or column from the discharge ports. In consequence of the action created by the forceful concentrated liquid column issuing from the device, certain novel results will become evident. As the relatively small but fast-moving solid stream of liquid is ejected from the discharge ports, the body of the still liquid, against which this stream is directed, will be forcibly moved in the direction of the stream, and will be displaced by the latter. At the same time the still liquid, immediately surrounding that fast moving small stream of liquid will be caused to move with and will augment the area and the moving force of the stream. Thus a relatively small-volumed but fast-moving solid column of liquid propagated within a large still body of liquid will rapidly move relatively large portions of that still liquid. As now these large portions of the still liquid are moved, the space theoretically emptied by them becomes immediately filled by equal portions of the liquid behind them. Thus a rapid and violent turbulence of the entire formerly still body of the liquid is produced.

The method of moving large bodies of liquids by means of rapidly moving small streams of liquid is not to be mistaken for the well-known ejector principle, since it is based on entirely different theories and achieves entirely different results, as is clearly evident from the foregoing explanation. On the other hand, it is readily conceivable that a device for creating a concise, fast moving stream of liquid within a still body of liquid may be utilized for propulsion of movable means equipped with my device. Thus, for instance, I visualize a ship equipped with my device for providing a stream of fast moving water directed into the relatively still body of water of the sea, whereby propulsion of the ship results through the reaction of the still water against the action of the fast moving column of water issuing from the device. This type of propulsion again should not be confused with ship propulsion by propellers where the propeller acts as a screw and the water as a nut.

While in the foregoing the device and the method are described in connection with relatively heavy fluids, my invention may also find application in the field of gases and especially air. In any event however my method is predicated upon bringing to a violent motion a relatively small portion of a fluid medium within a substantially static body of fluid medium, and wherein the progress of the violently propagated small body of the liquid medium within such static body of the medium is substantially one-directional or linear.

Furthermore my method contemplates to define the shape or form of the violently propagated streams of a liquid medium within a still large body of such medium. That form must be concise. It may be substantially cylindrical or in the shape of a converging cone, or in any other effective form, however its body must be so-to-speak solid or concentrated, so that when the stream or column is ejected it will be effective for a substantial distance from the place from which it issues. It will then produce the desired concentrated and sustained thrust necessary to achieve the results indicated. It has been found that the force of a column having the aforesaid characteristics will not be readily dissipated if its cross section remains substantially uniform, or reduces rather than gains in size. Thus, for instance, the effectiveness of an ejected column which would broaden in cross section, such as a diverging cone, will not be as effective as a column which would narrow in cross section during its progress. Such narrowing column may be obtained by inclining the discharge ports towards the longitudinal center axis of the device.

While the foregoing is directed toward the aim of producing rapid and violent movement of relatively large, still bodies of liquid media, my invention should be also considered from the standpoint of providing propulsion or steering by way of reaction. Thus it may find useful applications in powering or steering of surface ships or aircraft, the steering action being produced by changing the position of the device.

In the foregoing the word "one-directional" is used in connection with the description of the type of stream or column produced by my device. This term is intended to imply that such stream or column is truly linear, that is to say that all its portions issuing from the plurality of parallel, peripheral and axially disposed stator ports are propagated in straight, parallel lines, and that the resulting powerful stream or column does not deviate from its intended straight-line course, nor does it rotate or assume a helical form, since such deviations would defeat the intended purpose and function of the device.

Obviously the description of the specific embodiments illustrated in the drawings serve merely for the purpose of explaining the principle of my invention and not in a limiting sense. Similarly, while only one of the devices is illustrated being placed in a vessel, any number of means for creating a plurality of fast-moving liquid streams may be placed in a container at various heights or at different angles, especially when such vessel is of a large size. Thus, while I have been more or less specific in describing parts of my devices, it is obvious that changes and improvements may be incorporated therein, without departing from the underlying principle and broad scope of my invention, as defined in the annexed claims.

1. I claim: In a device of the class indicated, a stator comprising two telescoping members and a rotor operative between them, one of the stator members being cup-shaped and having in its cupped end portion an intake port so constructed that a peripheral ledge is provided at the cupped end portion the other stator member having a plurality of axially arranged vanes forming in conjunction with the first member a plurality of axially disposed discharge ports, the rotor having a head and a plurality of impeller vanes in cooperation with the intake port and the discharge ports of the respective stator members, the rotor head being adapted to cooperate with the ledge of said one stator member.

2. In an propulsion device for fluid matter, a power source, impeller means driven thereby and adapted to operate within a body of fluid matter, said means comprising a stator and a rotor, the stator being composed of two telescoping members between which the rotor operates, the exterior stator member having a central intake port, a plurality of axially disposed discharge ports formed between the two stator members, a drive shaft for the rotor passing through said intake port, and a journal for the drive shaft provided in the interior stator member near the discharge end of the discharge ports.

3. In a propulsion device for fluid media in confinement, a motive source operative from without such media, a stator and rotor assembly operative within such media, means for supporting the assembly and means for transmitting power from said motive source to the rotor of the assembly, said assembly comprising telescoping stator members and a rotor operative between them, the outer stator member forming a cup with a central opening in its bottom and a guide flange, the inner stator member having a cylindrical center and a plurality of vanes extending angularly from the center and forming discharge ports with the wall of the outer member, the rotor comprising a hollow head with inclined vanes, and a reduced center portion journaled in the center of the inner member, the rotor head operating between the flange of the outer stator member and the inner ends of the vanes in the inner stator member, said power transmitting means extending into said reduced center portion of the rotor and being removably secured thereto.

4. In a propulsion device for and adapted to be bodily immersed in a liquid medium, a stator having a central intake for the reception of an axial stream of such medium, and axially directed discharge means for axially ejecting said medium, and a rotor operative between said intake and discharge means for drawing in a central, axial stream of said medium and for forcing it through said discharge means, said stator comprising two telescoping members, the inner member having parallel, axially disposed vanes in intimate contact with the cylindrical interior of the outer stator member, the cooperation between these members forming a plurality of axial compartments constituting the discharge ports, said rotor having a central sleeve extension journaled in the inner stator member.

5. In a device for the purpose indicated, a two-part stator having intake and discharge ports and a rotor operative between the two stator parts, the intake port being disposed centrally, the discharge port comprising a plurality of peripheral, substantially parallel, axially directed passages for producing a straight-line discharge, said

stator comprising two telescoping members, the inner member having parallel, axially disposed vanes in intimate contact with the cylindrical interior of the outer stator member, the cooperation between these members forming a plurality of axial compartments constituting the discharge ports, said rotor having a central sleeve extension journaled in the inner stator member.

6. The combination with a container for fluid media, of a propulsion device for and adapted to be operative within such media, said device comprising a motive source disposed exteriorly to said container and having a drive shaft extending into the container, a support for the drive shaft and for the working elements of the device provided between the motive source and said container, a liquid-tight member connecting the sup-

port with said container, said working elements comprising a stator and rotor assembly, the stator being composed of two telescoping members, the outer member being substantially cup-shaped and having a central intake port, the inner member having a plurality of parallel, axially disposed vanes forming, in conjunction with the outer member, axial discharge ports, the rotor being operative between the intake port and the axial discharge ports and having a central intake passage in registry with the intake port of the outer stator member and an axial extension journaled in the inner stator member, said drive shaft passing through said stator intake port and the rotor intake passage and engaging said axial extension of the rotor.

LESLIE C. FISHER.
